UNITED STATES PATENT OFFICE.

LORENZ IVERSEN, OF WEST HOMESTEAD, PENNSYLVANIA, ASSIGNOR TO MESTA MACHINE COMPANY, OF PITTSBURGH, PENNSYLVANIA, A CORPORATION OF PENNSYLVANIA.

STEAM HYDRAULIC PRESS.

1,028,356.

Specification of Letters Patent. Patented June 4, 1912.

Application filed June 21, 1911. Serial No. 634,619.

To all whom it may concern:

Be it known that I, LORENZ IVERSEN, resident of West Homestead, Allegheny county, Pennsylvania, have invented a new and useful Improvement in Steam Hydraulic Presses, of which the following is a full, clear, and exact description, reference being had to the accompanying drawings, forming part of this specification, in which—

10 Figure 1 is a vertical section of the press embodying my invention, one of the pull-back or lifting cylinders and part of one balancing cylinder being broken away; Fig. 2 is an enlarged vertical sectional view of 15 the valve portion of the press; Fig. 3 is an end view of the valve mechanism; and Figs. 4, 5, 6 and 7 are views partly in section and partly diagrammatic showing the different positions of the control valve.

20 My invention has relation to hydraulic presses, hammers, shears, and the like, which employ steam hydraulic intensifier apparatus; and relates more particularly to the valve mechanism employed for controlling the operation of the press.

25 An object of my invention is to provide valve apparatus of this character which can be operated by a movement of a single lever, which will be simple in its construction 30 and mode of operation; and in the use of which the movements of the press head or ram will always follow and be in the direction of the movements of the single-control lever.

35 The nature of my invention will be best understood by reference to the accompanying drawings, in which I have shown the preferred embodiment thereof, and which will now be described, it being premised, 40 however, that various changes can be made in the details of construction and arrangement of the several parts by those skilled in the art without departing from the spirit and scope of my invention as defined in the 45 appended claims.

In these drawings, the numeral 2 designates the bed of the press, 3 the vertically movable press head which is arranged to work within the cylinder 4.

50 5 designates one of the pull-back or lifting cylinders.

55 6 designates the intensifier cylinder, 7 the steam piston of the intensifier having a rod 8.

9 is the plunger of the press head 3.

10 designates hydraulic balancing cylin-

ders for the pull-back or lifting cylinders 5, these cylinders having liquid supply connections 11 with the accumulator 12.

13 designates the supply connection for 60 the hydraulic cylinder 4, and 14 is the check valve which normally prevents back flow of liquid out of the said cylinder.

15 designates the steam supply connection for the cylinder 6, which is controlled by a 65 vertically movable valve 16; and 17 is the exhaust for the cylinder 6 controlled by the vertically movable valve 18.

The parts thus far referred to are well known in the art, and form no part of the 70 present invention. They need not, therefore, be described in detail.

19 designates the casing for the control valve, this casing being in the form of a cylinder provided with the inlet ports 20 75 and 21 at different vertical heights and opening into a chamber 22 which communicates with the steam inlet passage 22^a. The casing 19 also has the exhaust port 23 opening into the exhaust chamber 24 which 80 communicates with or forms a part of the exhaust passage 17; and also has a port 23^a which registers with the steam passage 23^b leading to a cylinder 23^c whose piston is arranged to control the check valve 14 before 85 described. Seated within the valve cage 19 is a vertically movable cylindrical bushing 25 whose open upper end communicates directly with the steam inlet passage 15. This bushing is provided with an upper 90 inlet port 26 and a lower inlet port 27, an exhaust port 28, and two ports 28^a and 28^b which are arranged in different positions of the bushing to register with the port 23^a and passage 23^b. 95

29 is a valve member of spool form, which is seated within the bushing 25 and has a downwardly extending stem 30. This stem 30 extends downwardly through the lower end of the bushing and through the bottom 100 of the valve cage, and is formed with a slotted head 31 at its lower end, which engages a crank pin 32 on a crank arm 33 of a rock shaft 34. This shaft is connected by a link 35 with a crank arm 36 on a 105 shaft 37. Mounted on the shaft 37 is a peripherally grooved wheel or sheave 38, over which passes a cord, belt, or other flexible connection 39. This flexible connection 39 extends downwardly to the controlling lever 110 40, its two ends being connected to said lever at opposite sides of the lever fulcrum 41.

The shaft 37 also carries a cam arm 42, which is arranged to act upon a lever 43 having a lifting engagement with the depending stem 18^a of the exhaust valve 18. 5 The shaft 37 also has a crank arm 44 which is connected by a link 45 with a crank arm 46 on a shaft 47 having an arm or cam 48 adapted to act on the lever 49, which has a lifting engagement at 50 with the upwardly 10 extending stem 16^a of the intensifier cylinder inlet valve 16.

The actuating lever 40 is designed to have the different positions indicated in Fig. 1, as "raising", "return stop", "lowering", 15 "stop" and "forging". In Figs. 1 and 2 the parts are shown in the position which they occupy when the lever is in the "stop position" after having been moved upwardly from the "forging position". In 20 this position both the arms or cams 42 and 48 are out of operative contact with the respective levers 43 and 49, and the valves 16 and 18 are both closed. The revolution of the grooved wheel or sheave 38, through the 25 operation of the flexible connection 39 has moved the control valve into the position shown in these Figs. 1 and 2, in which the inlet ports 20 and 26 of the valve cage and bushing are in register, and the exhaust 30 ports 23 and 28 are also in register. The valve covers the bushing port 28^a, which is now in line with the casing port 23^b. Steam now flows from the inlet 15 through the open upper end of the bushing, and through the 35 ports 20 and 26 into the chamber 22, which is connected by a pipe 22^a with the pull-back cylinders to admit steam under the pistons thereof.

Fig. 4 shows the position of the valve 40 parts when the actuating lever has been moved to its extreme upper or "raising position". In moving to this position the valve 29 has moved downwardly to its lowered position; and in so moving has engaged 45 an interior flange 25^a at the lower end of the bushing 25 and has moved said bushing downwardly within the cage to its lowered position. The ports 20 and 26 are now out of register, but the ports 27 and 21 are in 50 registering positions, so that steam will still be admitted through the bushing to the pull-back cylinders. In this position, the port 28^b has been moved down into line with the port 23^a, thereby admitting steam to the 55 pipe 23^b. This actuates the cylinder 23^c to open the check valve 14 and permit some of the water to flow out of the hydraulic cylinder 4 so that the ram or press head can be permitted to rise. The valve spool 29 has 60 been moved down sufficiently so that its upper flange partially uncovers the port 28^b in this position to admit steam therethrough. The exhaust ports 23 and 28 are in line with each other, so that steam can exhaust from 65 the intensifier cylinder, the exhaust valve

18 having been opened by the action of the cam or crank 42.

In the position of the parts shown in Fig. 5, the lever is on the "stop-return" position. In this position, the valve spool is 70 simply moved upwardly to the extent shown by comparison of Figs. 4 and 5, and the only port change which has occurred is the partial uncovering of the port 28^b which is now below the top flange of the valve spool. This permits the check valve operating cylinder 23^b to exhaust through the spool valve and through the exhaust ports 23 and 28. Steam is still being admitted to the pull-back cylinders. 75

In the position of the parts shown in Fig. 6, the lever is on the "lowering" position. In this position it is desired to lower the press head or ram with respect to the work. This can only be effected by exhausting 80 steam from the pull-back cylinders; and this is the only position of the valve parts in which the supply is cut off to such cylinders and then opened to the exhaust. In this position, the valve spool has moved upwardly so as to partially uncover the aligned ports 21 and 27 below the top flange of the valve, so that the exhaust steam from the pull-back cylinders can enter through said ports and exhaust through the ports 23 and 28. The exhaust port 28^b for the cylinder 90 95 still remains open.

Fig. 7 shows the valve parts in the forging position. In moving to this position, the spool has engaged the bushing to move 100 it upwardly into the position shown and bringing the ports 20 and 26 into alignment and moving the ports 21 and 27 out of alignment. In coming to these positions, the wheel or sheave 38 has moved to actuate the 105 crank arm 44, the link 45, rock shaft 47 and crank arm or cam 48 into position to open the intensifier cylinder inlet valve 16. This completes the cycle of operations.

It will be seen that the press head or ram 110 exactly follows the movements of the control lever. That is to say, the control lever is moved upwardly to raise the press head or ram, and is moved downwardly to lower the same. This makes a simple and natural 115 movement of the lever in accordance with the operations desired.

The control valve described is simple in its construction and operation, since the only movable parts are a cylindrical sleeve or 120 bushing and a plain spool valve; and the same actuating movements which control these valve parts also control, at the proper times, the intensifier cylinder inlet and exhaust valves.

It will be understood that the valve mechanism herein described, which forms the subject of my invention, is not limited in its application to the particular press which is 125 illustrated and described; but that, on the 130

contrary, it is applicable to various forms of steam-hydraulic presses. It will also be obvious that various changes can be made in the details of construction and arrangement 5 of the parts without departing from the spirit and scope of my invention. Thus, the actuating connections between the lever and the valve stem may be changed, the form of the valve and of the bushing, together with 10 the ports thereof may also be varied; and the actuating connections for the intensifier inlet and exhaust valves can also be changed.

What I claim is:—

1. In a steam-hydraulic press or the like 15 having a press-head and pull-back or lift cylinder, a control valve comprising a valve cage having ports therein, a ported member movable within the cage, a valve member movable relatively to the ported member, 20 and also arranged to actuate the said member at the limits of its movement, and a single actuating device connected to the valve member, said valve member, ported member and cage being constructed and arranged in 25 different positions of the parts to control the raising and lowering of the press-head; substantially as described.

2. In a steam-hydraulic press or the like, 30 having an intensifier cylinder, a hydraulic cylinder, a relief device for said cylinder and pull-back or lift cylinders, of a controlling valve device for the pull-back cylinders and the relief device for hydraulic cylinder, said device comprising a valve cage or casing 35 having ports in communication with the ports leading to said cylinders, a member movable within the cage or casing and having coöperating ports, a movable valve movable relatively to said member and also 40 adapted to actuate the same, and means for actuating the valve; substantially as described.

3. In a steam-hydraulic press or the like, 45 the combination with an intensifier, a hydraulic cylinder, a relief device for said cylinder and pull-back or lift cylinders, of a compound valve device for controlling the pull-back cylinders and the relief device for hydraulic cylinders, said device comprising 50 a cage member having ports therein, a ported member movable within the cage, and a valve member movable relatively to the ported member and also arranged to actuate the said member at the limits of its 55 movement and a single control lever connected to said device to actuate the same, said lever having a direction of movement corresponding to the direction of movement of the press-head; substantially as described.

4. In a steam-hydraulic press or the like, 60 the combination with an intensifier, a hydraulic cylinder, having a relief device and pull-back or lift cylinders, of a controlling

valve device for the pull-back cylinders and the relief device of the hydraulic cylinder, 65 said device comprising a valve cage having ports communicating with the supply and exhaust connections of the said cylinders, a sleeve movable longitudinally within the cage and having ports which coöperate with 70 the ports of the cage, said sleeve having an open end communicating with a steam supply connection, a valve member movable within the sleeve and also adapted to move the sleeve, and actuating connections for the 75 valve member; substantially as described.

5. In apparatus of the character described, the combination with a ported valve cage, of a sleeve or bushing member arranged to move longitudinally within the cage and 80 having coöperating ports, a valve member movable longitudinally within the sleeve or bushing member, and also arranged to move said member, the movement of the valve and the sleeve controlling said ports, a rotatable 85 member, actuating connections between the rotatable member and the stem of the valve member, and a lever having an actuating connection with the rotatable member; substantially as described.

6. In apparatus of the character described, having an intensifier cylinder, and pull-back or lift cylinders, the combination with a control device for said cylinders comprising a ported valve cage, a ported sleeve or 95 bushing movable longitudinally within the cage, and a valve member movable within the sleeve or bushing and also arranged to effect the movement thereof, a rotary actuator for the valve member, separate inlet 100 and exhaust valves for the intensifier cylinder, and means operated by the actuator for opening and closing said valves at the proper times in the movements of the actuator; substantially as described.

7. In apparatus of the character described, having an intensifier cylinder, and pull-back or lift cylinders, the combination with a control device for said cylinders comprising a ported valve cage, a ported sleeve or 110 bushing movable longitudinally within the cage, and a valve member movable within the sleeve or bushing and also arranged to effect the movement thereof, a rotary shaft, means for rotating said shaft, connections 115 between said shaft and the stem of the valve member, separate inlet and exhaust valves for the intensifier cylinders, and means carried by said shaft for actuating said valves; substantially as described.

In testimony whereof, I have hereunto set my hand.

LORENZ IVERSEN.
